United States Patent Office.

HENRY C. REYNOLDS, OF MANCHESTER, NEW HAMPSHIRE.

Design No. 3,662, dated September 14, 1869.

DESIGN FOR THE "BIT" OF CHOPPING-AXES.

The Schedule referred to in these Letters Patent and making part of the same.

To all whom it may concern:

Be it known that I, HENRY C. REYNOLDS, of Manchester, in the county of Hillsborough, and State of New Hampshire, have originated and designed a new and original shape or configuration for manufacturing, in any convenient mode, the bit of axes used for chopping, or the bit of a common woodman's axe, of which the following is a full, clear, and exact description, reference being had to the accompanying drawings, making a part of this specification.

Figure 1 is a side view of the axe.

Figure 2 is an end view of the same.

Like letters indicate similar parts.

$x x x$, fig. 1, show the contour of the axe, the inner side having a curved line, and the outer or further side, a straight line for its ends, as this shape gives it greater efficiency in swinging to and fro, the handle being inserted on the inner side, at x'' . But my design or discovery is intended to apply to the bit of the axe, from its eye to the cutting-edge, without regard to the form of the poll.

After determining the size and weight of the desired axe, I then proceed to form its cutting-edge upon the following mathematical principles, that is, by

combining three arcs of circles of the following degrees, to form the cutting-edge:

The centre angle at c , fig. 1, formed by the radii $b c$ and $a c$, of forty degrees; the angle at a' formed by the radii $a a'$ and $a' a$, of eighty degrees, for the outer corner of the cutting-edge; and the angle at b' formed by the radii $b' b$ and $b b'$, of eighty-three degrees for the inner corner of the cutting-edge, the centres of the two last-described arcs being upon the radii of the first named arc, as shown in fig. 1.

The lengths of the smaller radii, $a' a$ and $b' b$, fig. 1, are in proportion to the radii $a c$ and $c b$, of the centre arc, as five to nineteen. The lengths of these several arcs, in degrees, are constant, but their radii will vary according to the size and weight of the desired axe.

What I claim, is—

The design of the bit of an axe of the shape and configuration substantially as described herein.

H. C. REYNOLDS.
